OSCAR W. FAUSER, OF BELLEROSE, NEW YORK, ASSIGNOR TO CONGOLEUM-NAIRN, INC.,
A CORPORATION OF NEW YORK

DESIGN FOR A RUG

Application filed November 10, 1930. Serial No. 37,601. Term of patent 3½ years.

To all whom it may concern:

Be it known that I, OSCAR W. FAUSER, a citizen of the United States of America, residing at Bellerose, in the county of Nassau and State of New York, have invented a certain new, original, and ornamental Design for a Rug, of which the following is a specification, reference being had to the accompanying drawing forming a part hereof.

The figure is a plan view of a section of a rug showing my new design, the illustrated body section of the rug bounded by the indicating lines $a-a'$, $b-b'$, $c-c'$, and $d-d'$, being continuously repeated throughout the entire body of the rug, the illustrated border section of the rug bounded in the indicating lines $a-a'$ and $b-b'$ being continuously repeated throughout the border of the rug and the illustrated border corner bounded by the indicating lines $a-a'$ and $d-d'$ being repeated in proper relation in the other three corners of the rug.

I claim:

The ornamental design for a rug substantially as shown and described.

In testimony whereof, I affix my signature.

OSCAR W. FAUSER.
